MOP MAKING MACHINE

Paul Domenk, Chicago, Ill., assignor to Boyle-Midway Inc., Chicago, Ill., a corporation of Delaware

Application August 18, 1945, Serial No. 611,394

6 Claims. (Cl. 300—16)

1

This invention relates to a machine for manufacturing cleaning mops of uniform quality at a high rate of speed.

Mops for cleaning generally comprise a number of threads of yarn maintained in parallel relation, as by stitching, for example. It has hitherto been the practice to manufacture such mops by relatively crude manual processes. In addition to making the resulting article relatively expensive, there has been a lack of uniformity of the article. Since mops are sold in quantity at low price, uniformity of quality is necessary. The principal part of the mop, yarn, should be present in uniform quantities in the mops. This has been impossible with the crude manual manufacturing methods heretofore used. Thus, varying tensions of yarns and a variable length of yarn due to vagaries of operators has resulted in a relatively high percentage of rejects.

It is clear that a mop with too much yarn involves a loss to the mop manufacturer, while a mop with too little yarn may not pass the buyer's specifications, and thus also represent a loss. Hence uniformity of quality is necessary to protect both the buyer and the seller.

In accordance with the present invention, mops may be manufactured at a relatively high rate of speed under uniform conditions to produce uniform articles. The resulting mops have a uniformity in quality generally characteristic of quantity production, and are produced at a cost heretofore considered impossible. By virtue of the high speed of manufacture from raw material to finished product, it is possible to reduce the daily inventory of mops-in-process to practically zero. In fact, the process of making a mop from the yarn may be carried out at such high speed that it is possible to eliminate entirely the existence of any inventory of goods-in-process at the end of any employment period, such as a day.

The elimination of any goods-in-process inventory over night represents a substantial advantage in increased safety of operation. Thus, the original yarn from which mops are made, as well as the finished mops, may be stored in adequate quarters so that protection against fire may be assured. Such storage of raw material and finished products is not burdensome. However, the storage of goods-in-process requires special handling and involves considerable expense if a fire hazard is to be avoided. By virtue of the invention herein, the elimination of unfinished goods as items to be stored over night represents a substantial advantage from the fire hazard standpoint.

2

The invention in general provides a machine whereby a team of two operators may cooperate to form a mop-making unit. In general, one operator controls the winding of yarn on a reel to form hanks. The reeled yarn is then transferred to another operator for stitching, to maintain the strands of the hank in parallel relation. The stitching is accomplished by disposing thin strips of textile material transversely of the strands of the hank and stitching the same together. The stitched hank is thereupon manipulated by the machine to free the same from the reel, and the empty reel is returned to the first operator for a new cycle of operation, while the freed hank is a finished mop ready for application to any suitable mop holder.

For a full description of the invention, reference will now be made to the drawings wherein:

Figure 1 is a side elevation of the entire machine 20 for manufacturing mops.

Figure 2 is a plan view along line 2—2 of Figure 1.

Figure 3 is a sectional view along line 3—3 of Figure 1.

Figure 4 is a view along line 4—4 of Figure 1.

Figure 5 is a sectional detail along line 5—5 of Figure 1.

Figure 6 is an enlarged elevation of that portion of the machine where the initial winding of yarn into hanks is accomplished.

Figure 6A is a sectional detail of the pitch control on the yarn winder, taken along line 6A—6A of Figure 6.

Figure 7 is a sectional view along line 7—7 of Figure 6.

Figure 8 is a section along broken-line 8—8 of Figure 6.

Figure 9 is a plan view of a reel upon which yarn is wound.

Figure 10 is an end view of this reel.

Figure 11 is a circuit diagram of the control system.

Referring first to Figures 1 and 2, the machine has one part 10 thereof at which an operator is stationed. This is the station where the making of the mop is initiated. At this portion of the machine, a predetermined amount of yarn is wound on a reel. The wound reel goes by conveyor to portion 12 of the machine where another operator is located. At portion 12 of the machine, a reel has a piece of fabric applied over the yarn along a central portion thereof, transversely of the strands of yarn, and the two are stitched together at a sewing machine station. 55 The stitched yarn, still on the reel and still at-

tached to the sewing machine thread, has the thread automatically cut therefrom, and the conveyor moves the reel and yarn toward portion 13 of the machine. At this portion of the machine, knives cut the yarn from the reel. The resulting mop blank is discharged onto one conveyor, while the reel is returned by another conveyor to portion 10 of the machine.

Referring now in detail to portion 10 of the machine, table 20 is provided having frames 21 and 22 extending upwardly from said table at two spaced points. Frame 21 carries a pair of spaced bearings 23 and 24 in which is journaled stub shaft 25. Shaft 25 carries collar 26 against which coil spring 27, disposed around shaft 25, may exert its force. Coil spring 27 extends between collar 26 and flange 28 of bearing 23. Coil spring 27 urges shaft 25 to the right of bearing 23 (see Figure 6) so that collar 26 will rest against bearing 24. Shaft 25, at its free end, carries tip 30 having slotted grip 31 symmetrically disposed with respect to the axis of shaft 25.

Frame 22 carries a pair of bearings 33 and 34 in which is journaled a length of shaft 35. Shaft 35 at the end opposite shaft 25 carries bolted thereon a grip fitting 36. Fitting 36 has a central projecting portion 37 and end projecting portions 38 and 39 shaped as shown in Figure 6. Shafts 35 and 25 form a pair of spindles for yarn winding. Shaft 35, at the end beyond bearing 34 (see Figure 8) extends through journal 41 to ball bearing 42. Ball bearing 42 is supported in annular block 43, which itself is supported by arm 44 (Figure 6) from table 20. Annular block 43 carries a pair of pins 45 and 46 diametrically disposed, and these pins serve as anchors for coil springs 47 and 48. Coil springs 47 and 48 have their other ends positioned by pins 49 and 50 generally co-linear with pins 45 and 46. Pins 49 and 50 are rigidly carried by movable head 51 of any suitable shape. Head 51 has bolted thereto, as by bolts 52 and 53, arms 54 and 55 which extend beyond annular member 43.

Arms 54 and 55 carry at their ends pins 56 and 57 anchored in ring 58, which is rotatable in groove 59 of coupling block 60. Coupling block 60 is bolted by bolts 61 and 62 to driven member 64 forming part of a clutch. This clutch is of the cone type wherein the cooperating driving and driven surfaces each form the frustum of a cone. Block 60 and driven member 64 are splined to shaft 35 by a spline 63.

Cooperating with driven clutch member 64 is driving clutch member 66 having clutch surface 67 adapted to be engaged by driven member 64. Driving member 66 is journaled upon bearing 41 and has pulley surface 68' formed thereon. Belt 68 may couple driving member 66 to some suitable source of power such as a motor not shown.

Block 51 has aperture 70 therein into which plunger 71 projects and fits snugly. Plunger 71 may have collar 72 so that the plunger may exert a pushing force on block 51 and move the same against the compression of springs 47 and 48. Plunger 71 operates in air cylinder 73 and carries piston 74 within said cylinder. Piston 74 may have suitable packing 75 carried by bolt 76. Cylinder 73 is formed in block 77, this block having channel 78 giving access to cylinder 73. Channel 78 has fitting 80 screwed in, and this fitting is connected by pipe 81 to air valve 82 controlling air in an air supply pipe 83. Air valve 82 is controlled by an electric solenoid 84. Solenoid-controlled air valves are well known in the art, and hence a detailed description of conventional

solenoid-controlled air valve 82 is deemed to be unnecessary.

It is clear that, when solenoid 84 opens valve 82 to allow air from pipe 83 to go into pipe 81, piston 74 will be moved to the left, as seen in Figure 8. The air pressure and piston area are so related that plunger 71 is moved to the left, as seen in Figure 8, to force driven member 64 into driving engagement with driving member 66. The force exerted by plunger 71 to cause clutch engagement will be against the compression of springs 47 and 48. It is clear that, as soon as the air pressure is released, these springs will cause the clutch to disengage.

Between fitting 36 and 30, at the free ends of the two shafts 25 and 35, respectively, a reel, shown in detail in Figures 9 and 10, is adapted to be disposed. This reel, generally indicated as 86, consists of a pair of side members 87 and 88 provided with central cut-outs 89 and longitudinal members 90 and 91. Side members 87 and 88 may be of one thickness and of any material such as wood or fiber, while longitudinal members 90 and 91 may be formed of two thicknesses, as shown in Figure 10. By sandwiching the ends of side members 87 and 88 between the two thicknesses of longitudinal members 90 and 91, rabbet-like groove 93 will be formed longitudinally of each member 90 and 91 at the outer edge.

It will be apparent from the description of the apparatus thus far that reel 86 may be disposed between shafts 25 and 35 by the mere springing of shaft 25. With a reel disposed as shown in Figure 6, engagement of the clutch will cause reel rotation. As has been mentioned before, reel rotation is utilized for winding yarn thereon. To this end, table 20 may carry a number of spools of yarn. Thus, as an example, three spools 95, 96 and 97 are shown. It is manifest that one spool may be used or any number, depending upon the amount of yarn desired and the speed of winding. Spools 95, 96 and 97 may be carried on vertical spindles 98 in any desired position and, as shown, the yarn is preferably disposed below and somewhat to the rear of the reel in winding position. Yarn from spools 95, 96 and 97 is passed through guiding eyes 99, 100 and 101 and pulleys 102 carried by bar 103 parallel to the axis of shafts 25 and 35. Bar 103 is mounted for longitudinal movement in support 21 and frame work 105 carried by support 22. Additional eyes and guides for the yarn, as shown in Figure 7, may be provided to insure smooth feed. Inasmuch as the control of yarn from a stationary yarn supply through a movable pitch control member is well-known in the winding art, a detailed description of the yarn winding is believed to be unnecessary.

It will be apparent that rod 103 with eyes 99, 100 and 101 control the pitch of yarn wound upon reel 86. Rod 103 is moved back and forth longitudinally by means of block 107 carrying thread-engaging member 108 cooperating with member 110. Member 110 has threads 111 and 112, these being right and left threads respectively. The pitch is coarse, and the entire arrangement is such that block 107 will travel in one direction until it gets to the end of member 110, and then the direction of movement will be reversed. Thus, block 107 will be moved back and forth along member 110 upon rotation of this member. This arrangement of threads and movable member is well known in fishing reels, textile winding and the like.

Threaded member 110 may be journaled in

frame members forming part of frame 105, and carries sprocket 113 at one end thereof. Sprocket 113 is engaged by chain 115, which chain may pass down to driving sprocket 116 (Figure 7) journaled for rotation, suitably beneath table 20.

Solenoid 84 is controlled by push-button 118 (Figure 2). Push button 118 also controls an electric timer 120 (Figure 1). Timer 120 is adapted to maintain the solenoid circuit closed and maintain the clutch in power transmitting position for a predetermined time, after which the solenoid circuit is opened and the clutch is released. Such switching systems wherein a circuit is maintained opened or closed for a predetermined time interval after the initial operation of a switch are well-known in the art. Thus, for example, in "Industrial Electronic Control" by Cockrell, 1944 edition, electronic timers are disclosed in chapter 19, beginning on page 177. There are many mechanical devices which will perform the same function. In general, timer 120 may be of the type having a needle to indicate the passage of time during each switching cycle. However, this is not essential since, after the operator has started the reel turning by closing push-button 118, further attention on the part of the operator is unnecessary during that winding cycle. The reel is turned at a constant speed for a predetermined time and, during this time, has a predetermined amount of yarn wound thereon. The yarn at the beginning of the winding operation may be given a turn or two, after which the reel rotation will continue the winding of the yarn. When the winding cycle has stopped, the operator cuts the yarn and pulls the wound reel out from the winding spindles.

Below the winding spindle and above table 20 is conveyor 122 of any desired construction. Conveyor 122 travels as shown in Figure 2 and conveys a wound reel to bin 123 (Figure 4). Thus, a wound reel reaches portion or station 12 in the mop making machine.

In this station, there is provided table 125 supported on suitable sides 126 and 127. Mounted on table 125 is a sewing machine 128 of the multi-thread, high speed, industrial type, capable of simultaneously sewing a plurality, here shown as three, lines of stitching, which is used to sew textile material across the reeled yarn to form the mop blank. Inasmuch as such machines have been on the market for many years and are well-known, no detailed description thereof will be given. Sewing machine 128 has a suitable pulley 129 for driving the same, said pulley being connected by belt 130 to motor 131 supported below table 125. Motor 131 may be controlled by treadle 132 for starting and stopping the same. An additional treadle 133 is provided, this treadle being connected by suitable connecting rod 134 for operating presser foot 135 of the sewing machine. As is well known, presser foot 135 must be raised above work plate 135' to introduce the work into sewing position, after which the cooperation of presser foot 135 and the usual feed bar in the base of the sewing machine serves to feed the work forwardly.

Beyond sewing machine 128 is a pair of spaced guides 136 and 137, extending away from the discharge side of the sewing machine to the discharge side of the entire machine. A certain distance beyond the sewing machine on the discharge side there is disposed a supporting frame work 138 consisting of side bars 139 and a cross bar 140. Cross bar 140 is supported above work plate 135' a distance sufficient to clear, gener-

ously, any reel while lying flat on the work plate. Cross bar 140 is provided at the center thereof with guide members 142 in which cutter 143 is vertically slidable. Cutter 143 has handle portion 144 to which is pivotally secured actuating lever 145. Lever 145 is pivotally mounted at 146 to support post 147 on cross bar 140. Lever 145 is actuated by any suitable power means such as compressed air motor 148 having a plunger 149 pivotally secured at 150 to lever 145. Air motor 148 may simply consist of a cylinder and piston and may be operated from air supply pipe 151 leading from air control valve 152 actuated by solenoid 153. As shown in Figure 5, cutter 143 is adapted to move vertically and is used to cut the threads extending between the sewing machine and the mop blank.

Beyond work plate 135' and substantially level with the same is conveyor 155. Conveyor 155 consists of two spaced sections which are moved as a unit in the direction of the arrow, as shown in Figure 1, by sprockets 156 and 157, respectively. One or both of these sprockets may be driven by a suitable motor (not shown). The space between the sections of conveyor 155 is clear for a short distance from cutter 143. At a predetermined point along the conveyor, which point will be obvious from a description of the machine to be given later, a source of light 160 is provided. This source is disposed above conveyor 155 and may be a hooded incandescent lamp having a light discharge opening 161. Light source 160 is adapted to flash a beam of light downwardly to photoelectric cell 162 disposed below the supporting plane of conveyor 155. Photoelectric cell 162 and light source 160 cooperate in such a manner that, in the absence of a mop blank carried by reel 36, the light will pass through to the cell. Upon interruption of the light, solenoid 153 will be actuated.

The system is so designed, preferably, as to provide a predetermined time delay after cut-off of light from the cell. The purpose of this will be apparent in connection with the description of the operation of the system. Photoelectric light systems are described on pages 158 to 166 inclusive of "Industrial Electronic Control," previously mentioned. In addition, the timing circuits discussed in chapter 15, page 129 of this book, are incorporated in apparatus available on the market so that a delayed action photoelectric control system is well known. As shown in Figure 1, the output of photoelectric cell 162 may go to a suitable amplifier and delay unit 164, which unit may control the circuit for solenoid 153.

Beyond the photoelectric system, in the direction of conveyor travel, a double strip conveyor 165 similar to conveyor 155 is provided, operating from sprockets 166 and 167 and driven by suitable motor (not shown). As indicated by the arrows in Figure 1, conveyor 165 has a portion thereof opposed to conveyor 155 travelling in the same direction. These two conveyor strips are vertically spaced a short distance apart and are adapted to engage sides 90 and 91 of a reel upon which yarn has been wound. At an intermediate point between sprockets 166 and 167, a pair of spaced cutters 168 and 169 (Figures 2 and 3) are provided. These cutters are circular discs lying in a horizontal plane and operating on vertical shafts. The cutters are driven by motors 170, one of which is shown in Figure 1.

As is manifest from Figure 3, cutter discs 168 and 169 extend through suitable slots in guards 75 171 and 172 and into grooves 83 of a reel as the

same travels on the conveyors. Thus, yarn wound around the reel is slit by these cutters.

Table 125 at portion or station 13 has opening 174 (Figure 2) formed therein, this opening being disposed below conveyors 165 and 155. Below table 125 at opening 174 is a transverse conveyor 175 travelling in the direction shown by the arrow. Carried by table 125 in proximity to sprockets 157 and 161 are standards 176 (Figure 1) carrying cross bar 177 (Fig. 2) upon which is supported stripper arm 178. Stripper arm 178 bends down so that free end 179 is in the center between conveyors 155 and 175 and in the path of travel of a reel. Arm 178 is preferably of spring material such as spring steel and, clearing sides 86 and 87 of a reel, presses down upon a mop blank to strip the same from the reel. The stripped blank drops through opening 174 to conveyor 175 and is removed.

Reel 83, stripped of its mop blank, continues on between the opposing conveyors and drops upon conveyor 197 (Fig. 2) whose active surface travels in the direction indicated by the arrow, namely toward conveyor 122. Conveyor 197 discharges reels into a deep narrow space 198 bounded by suitable guards and at the bottom of which there may be provided conveyor 199 to move the reels toward portion or station 10. Conveyor 199 is aligned with and is adapted to deliver reels to conveyor 199', which conveyor moves the reels to position 10. It will be noted that reels discharged from conveyor 197 are supported on their sides so that less room is used, and a reel delivered to position 10 may be readily grasped for insertion into the winding spindle.

In Figure 11 is shown a simple circuit diagram of the control circuit for the yarn winding portion of the mop making machine. Start switch 118 is connected by lead 180 to winding 181 of a relay. The relay circuit continues on to lead 182 of a power line having stop switch 183 therein and then goes on to lead 184 to timer 120. From lead 184, connection 184' is taken to a terminal of the start switch. From timer 120, a connection goes to movable contact 185 of the relay. Movable contact 185 cooperates with fixed contact 186 of the relay.

The relay also has an additional movable contact 187 cooperating with fixed contact 188 and controlling clutch-control solenoid 84. Timer 120 may be connected to a suitable source of power for operating the same.

Start switch 118 is normally open. Upon the operator closing the same, a circuit consisting of lead 184, switch 118, lead 180, relay winding 181 and lead 182 is established. Movable contacts 185 and 187 are closed. When movable contact 185 closes against fixed contact 186, timer 120, which is normally closed, completes a shunt around start switch 118. Thus, even though switch 118 is opened by the operator withdrawing the pressure, the system remains locked in operating position. At the same time, movable contact 187 closes the clutch control solenoid circuit. After a predetermined time interval, timer 120 opens the shunt circuit, and the system reverts to its non-operating condition. Timer 120, after a short interval of time, assumes its normal closed position so that the circuit condition, as shown in Figure 11, is that immediately prior to the operator's pressing button 118. Stop switch 183 is provided so that emergency stopping may be obtained.

The operation of the entire machine is as follows. An operator is at station 10 and grasps

empty reel 86 and springs the same into the winding spindle. This is accomplished by moving the spindle against the bias of its spring and positioning the same for winding. The operator takes the loose ends of the yarn and turns the same around one of sides 90 and 91 of the reel. The operator then presses push-button 118. This actuates the relay which throws in the clutch and starts the reel turning. Timer 120 begins to operate. Throwing in the clutch by power controlled means results in uniform and quick starting of the winding. The timer controls the winding time and, at the end of a predetermined period, say 10 or 12 seconds, for example, the clutch is thrown out and the winding stops. Thus, accurate control of the winding on reel 86 is provided. During this winding, the operator at station 10 may have moved to the corresponding station 10 of another machine and started another reel. With the winding stopped and a reel provided with its complement of yarn, the operator springs a reel from its winding spindle and cuts it from the source of the yarn. The reel with the yarn wound around it is then dropped on conveyor 122 and travels toward bin 123.

An operator at station 12 picks up a wound reel and disposes the same in position for sewing. At the same time, the operator disposes a length of textile fabric 173 along the center of the yarn lengthwise, as seen in Figure 2. Strip 173 is thus perpendicular to the direction of the individual strands of yarn. Strip 173 is preferably long enough so that the ends may be curled under the yarn to prevent the same from working loose. Stitching 173' is applied by the sewing machine. As the reel and yarn pass through the sewing machine, it reaches the beam of light between light source 160 and cell 162. Thus, light is interrupted. Inasmuch as the reel and yarn have not yet passed through the sewing machine, the action of the photoelectric control is delayed. It is understood, however, that the photoelectric control means may be disposed far enough beyond the sewing machine so that no delay will be necessary. However, the feeding action of the sewing machine urges the reel and yarn forwardly, as shown in Figure 2, to the right. Thus, the reel and yarn are positively urged by the sewing machine onto conveyor 155.

By the time that a wound reel has passed through the sewing machine, the forward edge of the unit is well on conveyor 155 and will now be urged forward by this conveyor. The delay in the photoelectric unit is such that, when the reel and mop blank have passed through the sewing machine and beyond cutter 143, the cutter is actuated to cut the threads. By careful control of the timing of the various units, it is possible to cut the thread close enough so that long strands are not left.

The reel and mop blank continue on between conveyors 165 and 155 to cutters 168 and 169, where the mop blank has the yarn severed in preparation for stripping. The mop blank and reel continue on until they are over opening 174. In this position, stripping occurs with the mop blank dropping down to conveyor 175 while the free reel goes on to conveyor 197 and finally to conveyor 199 and conveyor 199' at station 10.

If desired, the motors for driving cutters 168 and 169 may be controlled by photoelectric cell 162 so that the cutters operate simultaneously with thread cutter 143. The duration of energization of cutters 168 and 169 may be controlled

by various means well known in the art. In actual practice, the inertia of the motor rotor and cutters will tend to keep the cutters rotating during normal operation of the entire machine.

It is manifest that by virtue of the machine disclosed herein a team of two operators can work at high speeds in the manufacture of mops. The various steps in mop making are carried out with maximum speed and efficiency, and the mops themselves are uniform as to quality.

I claim:

1. A mop making machine comprising a flat reel, means for winding yarn on said reel to form a hank, means for conveying said winding reel to a sewing machine, means for sewing a textile strip along the center of said hank to tie said yarn together, means for cutting the yarn along the two edges of said reel over which the yarn is wound, and means for stripping said resulting mop blank from said reel.

2. A mop making machine comprising a flat rectangular hollow reel, means for winding yarn on said reel to form a hank having a predetermined amount of yarn thereon, means for conveying said wound reel to a sewing machine, means for sewing a textile strip transversely across said yarn along the center of the reel to tie said yarn to form a mop blank, means for cutting the yarn at the edge along the two sides of said reel over which the yarn is wound, and means for stripping said mop blank from said reel.

3. A mop making machine comprising a flat generally rectangular hollow frame constituting a reel, said reel having two sides each provided with a rabbeted groove, means for winding a predetermined amount of yarn over said reel, said yarn being wound over said two sides, a sewing machine, conveying means extending between said winding means and sewing machine, means for sewing a textile strip along the center of said wound yarn and perpendicular to the individual yarn loops, cutters having cutting edges extending into said reel grooves for cutting the yarn, and means for stripping the mop blank from said reel.

4. The structure of claim 3 wherein photoelectrically controlled means are provided after said sewing machine to cut the thread for sewing after said sewing operation has been completed.

5. A mop making machine comprising a flat hollow generally rectangular frame reel, a pair of spindles for rotating said reel on an axis, a source of power, a clutch between said power source and said spindles, power controlled means for engaging said clutch to turn said spindles, a yarn supply, means for winding said yarn on

said reel as said spindles turn, said means including means for guiding said yarn along said reel to lay said yarn evenly, time controlled means for disengaging said clutch after a predetermined winding cycle, a sewing machine, a conveyor extending from said winding spindles to said sewing machine, means for releasing said wound reel from said winding spindles and dropping the same on said conveyor after a predetermined winding cycle, means for sewing a textile strip transversely to said yarn loops along the center of said reel, means for cutting the yarn at the reel sides where the yarn goes around a reel side to form a mop blank, and means for stripping said mop blank from said reel.

6. In combination in a mop-making machine having a winding station, a sewing station and a cutting station: at the winding station means for rotating a flat reel having an open center and a recessed slot along each longitudinal edge, means for mounting and demounting said reel in said rotating means, and a yarn-supply spool adapted to feed yarn to the rotating flat reel to wind yarn thereon; conveyor means for transporting the yarn-wound reel to the sewing station; at the sewing station a sewing machine so positioned as to permit passage of said flat reel longitudinally under the sewing head and adapted to sew a strip of fabric to the yarn wound thereon, and cutting means for severing the thread after completion of the sewing operation; mechanical conveyor means for transporting the reel longitudinally from the sewing station to the cutting station; and at the cutting station means to advance the reel longitudinally and a pair of knives, one so positioned on each side of the reel as to enter the longitudinal slot and thereby cut the yarn from the reel as the reel is advanced longitudinally through the cutting station.

PAUL DOMENK.
